(74) Attorney, Agent, or Firm — McAndrews, Held & Malloy, Ltd.

(57) **CLAIM**

The ornamental design for a speaker, as shown and described.

DESCRIPTION

FIG. 1 is a front perspective view of a speaker showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof;

FIG. 9 is an enlarged view of the encircled portion 9 in FIG. 3;

FIG. 10 is a front perspective view of the stand portion of the speaker shown separately for clarity of illustration;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof; and,

FIG. 16 is a bottom plan view thereof.

The evenly dashed broken lines in the drawings illustrate example environment and portions of the speaker that form no part of the claimed design. The dot dashed broken lines encircling portions of the claimed design that are illustrated in enlargements form no part of the claimed design.

1 Claim, 16 Drawing Sheets
